SHEET ROLLING DEVICE

Fermer A. Malone, Dallas, Tex.

Application March 15, 1956, Serial No. 571,679

10 Claims. (Cl. 242—74.1)

This invention relates to new and useful improvements in stands for rolling sheet material.

One object of the invention is to provide an improved stand having a reel for rolling sheet material thereon to facilitate handling, packaging and shipping of the material.

Another object of the invention is to provide an improved stand, of the character described, wherein the reel is of such construction that sheet material may be readily wound thereon and removed in roll form therefrom, which material may be relatively thin, light-weight and difficult to handle, such as sheet plastic.

A further object of the invention is to provide an improved stand, of the character described, wherein the reel includes novel clamp means adapted to be readily engaged with and disengaged from sheet material whereby the material may be easily and quickly connected to and wound on said reel and removed therefrom.

A construction designed to carry out the invention will be hereinafter described, together with other features of the invention.

The invention will be more readily understood from a reading of the following specification and by reference to the accompanying drawing, wherein an example of the invention is shown, and wherein:

Fig. 1 is a perspective view of a stand constructed in accordance with the invention.

Fig. 2 is an enlarged, perspective view of an upper portion of the reel of the stand, its clamp and latch,

Fig. 3 is a top plan view of the stand with the clamp engaged, and

Fig. 4 is a transverse, vertical, sectional view of the lower portion of the stand.

In the drawing, the numeral 10 designates an upright stand embodying the principles of the invention and including a flat, horizontal base 11 which is preferably circular. An axial, upstanding pin or spindle 12 is carried by the base for supporting an upright reel 13 by its longitudinal, tubular axle or mandrel 14 (Fig. 4). Preferably, a suitable bearing 15 is interposed between the base 11 and the tubular axle 14 to facilitate rotation of the reel 13 relative to said base and its spindle 12. The reel is substantially cylindrical and is adapted to support sheet material M (Fig. 3) which is wound on said reel to facilitate handling thereof. Usually, the material is relatively thin, light-weight and difficult to handle, such as sheet plastic. After the desired length of material has been rolled or wound on the reel, it is adapted to be removed in roll form by sliding the same upwardly off of said reel.

The reel 13 includes a plurality of substantially annular or circular, circumferential bands or rings 16 connected in substantially parallel, spaced relationship by longitudinal bars or members 17. One of the bands 16 is provided at each end of the reel and the bars 17 are substantially coextensive with said reel. Substantially radial arms or members 18 are provided for

2

connecting the circumferential bands to the tubular axle 14. For imparting rotational movement to the reel, a crank 19 is provided at the upper end of said reel and includes an arm 20 telescopingly mounted in a complementary housing 21 (Figs. 1-3). Suitable supporting legs 22 depend from the housing 21 for connection with the closed upper end 23 of the shaft 14 and one of the radial arms 18. The crank housing terminates inwardly of the exterior of the reel and the arm 20 is of such length to permit telescoping thereof inwardly of said reel exterior, whereby the telescoped crank does not interfere with the upward removal of rolled sheet material from the reel.

As shown most clearly in Figs. 2 and 3, each annular or circumferential band 16 is interrupted to provide an opening 24 between its ends and one end, preferably the clockwise end, is offset inwardly of the other end. The openings 24 are vertically aligned and coact to provide a substantially coextensive and continuous, longitudinal opening for the reel for receiving an end of the material M. One of the longitudinal bars 17 underlies and is secured to the outwardly positioned or counter-clockwise ends of the bands 16. Instead of the radial arms 18, the spaced ends of each band are connected to the axle 14 by a pair of substantially parallel arms or members 25 with the clockwise member being of less length than the other member (Fig. 3).

For confining one end of the sheet material in the reel opening, a clamp 26 is mounted in the openings 24 for engagement with the clockwise ends of the bands 16. The clamp includes an elongated, actuating element or rod 27 extending longitudinally of the reel and having a handle 28 on its upper end. Suitable bearing members or plates 29 extend between the inner portions of the arms 25 for rotatably supporting the actuating rod 27 adjacent the axle 14. A plurality of transverse clamp arms or members 30 are connected to the rod by suitable collars 31 immediately below the plates 29 whereby the clamp arms extend outwardly between the pairs of reel arms 25. A longitudinal clamp bar or member 32 is secured to the outer ends of the arms 30 for overlying engagement with the outer portions of the bands 16 adjacent their clockwise ends. As shown in Fig. 3, the clockwise ends of the bands are engaged by the outer end portions of the clamp arms and the inward offsetting of said band ends provides space for accommodating the clamp bar 32 whereby said clamp bar is disposed within the circular contour of the reel. By swinging the handle 28, the actuating rod 27 is rotated for swinging the clamp 26 into and out of engagement with the clockwise ends of the circumferential bands 16.

In order to hold the clamp in such engagement, a latch 33 is provided and includes a rock shaft 34 having a handle 35 at one end. A pair of apertured lugs or ears 36 project upwardly from the arms 25 at the upper end of the reel 13 to rotatably support the shaft 34 in overlying, transverse relation to said arms and the clamp arm 30 therebetween. The intermediate portion of the shaft has a wedge-shaped dog or element 37 projecting laterally therefrom for engagement with the uppermost clamp arm 30 and the counter-clockwise reel arm 25 so as to hold the clamp 26 engaged with the clockwise ends of the bands 16 to confine one end of the sheet material M therebetween as shown in Fig. 3, whereby said material is attached to the reel for rolling thereon.

In order to facilitate rolling of the material on the reel, a guide 38 encircles the lower portion of said reel in concentric, spaced relationship. The guide 38 includes a plurality of upright posts or rods 39 mounted on the base 11 and having their upper ends connected by a substantially annular band or ring 40. Preferably, the guide surrounds at least the lower half of the reel.

The ends of the band are spaced from each other, with one end being welded or otherwise secured to one of the posts 39 and its other end being connected to an adjacent, elongated post or rod 41 which is substantially coextensive with the reel. A substantially coextensive angle bar or member 42 is carried by the elongated post 41 to provide a straight edge and flat surface which facilitates cutting or severing of the sheet material M.

As has been explained, the sheet material M is rolled onto the reel 13 until the desired length is obtained. When the latch 33 is disengaged as shown in Fig. 2, the clamp 26 may be swung out of engagement with the clockwise ends of the bands 16 to permit the insertion of the free end of the material therebetween. Upon re-engagement of the clamp and latch, the material is connected to the reel and wound thereon (Fig. 3) by turning the crank 19. Manifestly, the circular guide 38 assists in the rolling of the material which may be cut or severed at the straight edge and flat surface provided by the elongated angle bar 42. The material may be readily removed from the reel in roll form by sliding said material upwardly after telescoping the crank arm 20 within the crank housing 21. It is noted that the clockwise end portions of the bands 16 function as abutment means for coacting with the clamp.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A stand for rolling sheet material including a base, an upright cylindrical reel rotatably supported by the base, the reel including an axial supporting member, exterior members extending circumferentially of said reel, arms extending transversely between and connecting the supporting member to the exterior members, said exterior members being interrupted to provide an opening extending longitudinally of said reel for receiving an end of sheet material, clamp means mounted in the opening for engagement with the portions of the exterior members adjacent said opening, and latch means at the upper end of said opening for holding the clamp means in such engagement for confining the end of the sheet material.

2. A stand as set forth in claim 1 wherein certain of the transverse arms of the reel are disposed in adjacent pairs with one arm of each pair on each side of the opening, the clamp means being supported by and between the pairs of arms.

3. A stand as set forth in claim 2 wherein the clamp means includes a bar substantially coextensive with the opening, an actuating rod extending longitudinally of and rotatably mounted in the reel, and arms extending transversely between and connecting the upper and lower ends of the bar and rod.

4. A stand as set forth in claim 3 wherein the latch means coacts with the upper arm of the clamp means.

5. A stand as set forth in claim 1 including substantially cylindrical guide means encircling the reel in spaced relationship.

6. A stand as set forth in claim 5 wherein the guide means includes an upright member substantially coextensive with the reel.

10 7. A stand as set forth in claim 1 wherein the clamp means includes an actuating rod extending longitudinally of and rotatably mounted within the reel, arms extending transversely from the rod between several of the arms of said reel, and means on the outer ends of the clamp arms for engaging the portions of the exterior members adjacent the opening of said reel.

15 8. A stand for rolling sheet material including a base, a reel rotatably mounted on the base and having a substantially cylindrical exterior upon which sheet material is adapted to be wound, the reel having a longitudinal opening in its exterior for receiving an end of the sheet material, a clamp bar substantially coextensive with the longitudinal opening and within the circular contour of said reel, an actuating rod extending longitudinally of said reel and rotatably mounted therein, clamp arms extending transversely between and connecting the clamp bar and rod, abutment means at said opening for coacting with the clamp bar, and latch means for holding said clamp bar in engagement with the abutment means for confining the end of the sheet material.

20 9. A stand as set forth in claim 8 wherein the clamp arms are disposed at the ends of the longitudinal opening of the reel, the latch means being mounted adjacent one end of said opening for engagement with one of said clamp arms.

25 10. A stand for rolling sheet material including a base, a reel rotatably mounted on the base and having a substantially cylindrical exterior upon which sheet material is adapted to be wound, the reel having a longitudinal opening in its exterior for receiving an end of the sheet material, clamp means extending longitudinally of the opening and within the circular contour of said reel, abutment means at said opening for coacting with the clamp means, latch means for holding said clamp means in engagement with the abutment means for confining the end of the sheet material, said reel including a plurality of circumferential members, axial mounting means, and arms extending transversely between and connecting the members to the mounting means, said reel opening being formed in said members and portions of said members forming the abutment means.
